UNITED STATES PATENT OFFICE

THOMAS E. TAYLOR, OF MANSFIELD, OHIO, ASSIGNOR TO THE TAPPAN STOVE COMPANY,
OF MANSFIELD, OHIO, A CORPORATION OF OHIO

OVEN DOOR CONSTRUCTION

Application filed July 23, 1930. Serial No. 469,974.

This invention relates to a stove construction and particularly to an improved type of oven door construction. In many places the gas supply available for use in gas stoves is the so-called "wet" gas, that is, a considerable amount of moisture is liberated as a product of combustion. Inasmuch as the oven walls are often cold when the burner is first lighted, it commonly occurs that the moisture thus liberated condenses on the oven walls and particularly on the door. In some cases there is a sufficient condensation to cause an entirely undesirable amount of water to run out around the edges of the oven door and cause deterioration of the floor varnish or other undesirable effects.

Accordingly, it is the object of this invention to provide an oven door which when closed will prevent the escape of moisture and retain the same within the oven until the temperature rises to such a point that it is evaporated. A further object is to provide a trough along the lower portion of the oven door to catch moisture condensing on such door and retain the same until it can be evaporated. Other and more specific objects will become apparent as the description proceeds.

In the drawing Fig. 1 is an elevational view of an oven door according to my invention; Fig. 2 is a vertical section taken through such door and adjacent the stove parts; Fig. 3 is a horizontal section through such door and adjacent parts; and Fig. 4 is a fragmentary detail of a modified form showing the attachment of a sealing strip to the oven parts instead of to the door parts.

The portions of the oven with which the door cooperates are composed of wall members 10 connected in any suitable manner to an insulated wall portion 11. The wall portion 10 preferably takes the form of a facing strip provided with an angular wall 10^a with which an edge of the door is adapted to cooperate and shoulders 10^b adapted to limit the door member.

The door consists of opposed flanged telescoping shells 12 and 13 between which is contained a suitable insulating material 14. Extending along the top and vertical sides of the door is a continuous V-shaped sealing

strip 15. This strip has one of its edges extending between the flanges of the telescoping shells 12 and 13 and is fastened in such position as by means of rivets 16. The other edge extends outwardly at an angle and is adapted to form a close sealing contact with the angular portion 10^a of the wall member 10. This strip is preferably made of resilient sheet metal. Along the bottom of the door and extending between the hinge and bracing members 17 is a trough-forming sealing strip 18 consisting of a resilient V-shaped metallic strip secured between the telescoping flanges of the portions 12 and 13 and forming with the wall 12 of the door a trough to retain moisture condensed on the portion 12. The ends of the strip 18 may be sealed to form a water-retaining trough by solder or any other suitable means.

In Fig. 4 I have shown a modification in which the sealing strip 20 is attached to the angular portion 10^a of the wall 10 as by a rivet 21 and cooperates with the edge of the door to effect a moisture seal as will be obvious from the drawing.

While I have shown and described certain illustrative embodiments of my invention I wish it understood that the same is susceptible of variation and that I am limited only in accordance with the appended claims.

Having thus described my invention, what I claim is:

1. An oven door including a trough adjacent the bottom thereof adapted to collect any moisture condensing on such door due to the use of "wet" fuel and to retain the same until the oven reaches a temperature sufficient to evaporate it, said trough comprising a metal strip extending along the bottom edge of the door and projecting inwardly and upwardly therefrom.

2. An oven door construction including a door means and wall means defining an opening within which such door means is received and a bent, metallic sealing strip attached to one of said means and adapted to coact with said other means to seal said opening against passage of moisture, said strip serving to collect and retain any moisture which may be precipitated on the inside of the door.

3. An oven door construction including a door means and wall means defining an opening within which such door means is received and a bent, metallic sealing strip attached to one of said means and adapted to coact with said other means to seal said opening against passage of moisture, said strip being shaped to provide a trough extending along the lower edge of the door and projecting inwardly and upwardly therefrom so as to collect any moisture which may be precipitated upon the inside of the door. 75
4. An oven door construction including a door means and wall means defining an opening within which such door means is received and a bent, metallic sealing strip attached to one of said means and shaped to provide a trough extending along the lower inner edge of the door and projecting inwardly and upwardly therefrom. 80
5. An oven door including flanged, opposed, sheet-metal shell members telescoping one within the other and a retrorse, curved, generally V-shaped member having one leg interposed between the telescoping flanges and the other outside thereof, the bight portion extending upwardly and forming with one shell member a trough. 85
6. An oven door including flanged, opposed, sheet-metal shell members telescoping one within the other and a retrorse, curved, generally V-shaped member having one leg interposed between the telescoping flanges and the other and shorter one outside thereof, the bight portion extending upwardly and forming with one shell member a trough. 90
7. An oven door including flanged, opposed, sheet-metal shell members telescoping one within the other and a retrorse, curved, generally V-shaped member having one leg interposed between the telescoping flanges and the other outside thereof, the bight portion extending upwardly and forming with one shell member a trough, said V-shaped member being resilient and serving as a seal for the bottom of the door in addition to its function as a trough. 95
8. An oven door construction including a door means and wall means defining an opening within which such door means is received and a bent, metallic sealing strip attached to one of said means and adapted to coact with said other means to seal said opening against passage of moisture, said strip extending along the lower inner edge of the door and shaped to receive and retain the moisture which may be deposited upon the inner surface of the door. 100
9. An oven door construction including a door and wall means defining an opening within which said door is received, said door comprising spaced shell members fitting one within the other and a generally V-shaped metallic sealing strip having one leg disposed between said shell members and the other leg 105
- 110
- 115

disposed outside of said shell members and forming a seal between the edges of said door and said wall means.

In testimony whereof I hereunto affix my signature. 70

THOMAS E. TAYLOR.
